UNITED STATES PATENT OFFICE.

GUSTAF DALÉN, OF STOCKHOLM, SWEDEN, ASSIGNOR TO AMERICAN GASACCUMULATOR COMPANY, OF PHILADELPHIA, PENNSYLVANIA, A CORPORATION OF NEW JERSEY.

DIAPHRAGM-VALVE.

1,011,922.

Specification of Letters Patent. Patented Dec. 19, 1911.

Application filed December 4, 1909. Serial No. 531,454.

To all whom it may concern:

Be it known that I, GUSTAF DALÉN, a subject of the King of Sweden, residing in Stockholm, Sweden, have invented certain 5 new and useful Improvements in Diaphragm-Valves, of which the following is a specification.

In valves of this character in which a diaphragm is adapted to be depressed against 10 a seat for closing the valve, the seat has heretofore been provided with a coating of tin in order to provide a softer metal against which the diaphragm may contact. The purpose of providing the coating of tin has 15 been to insure the tight closing of the valve opening by the diaphragm to prevent leakage. In diaphragm valves of the character of this invention the diaphragm is usually made of steel and it will be understood that 20 when the same is forced against the tin coating of the valve seat the tin yields sufficiently to insure complete closure of the valve. This form of construction, however, is objectionable for the reason that after 25 having been used for some time the coating of tin is worn away and in consequence of which the diaphragm fails to effect a tight closing or closure of the valve,—permitting the valve to leak. In order to prevent or 30 stop such leakage it has been necessary heretofore to separate the parts of the valve and retin the valve seat, such retinning necessitating the heating of the valve body.

The object of my invention is to obviate 35 or eliminate the objectionable features above pointed out and the inconvenience and trouble of retinning. To effect such object I employ a disk of suitable soft metal, such as copper, aluminum or the like, which is 40 placed above the seat and is provided with openings for the valve channel. If the valve is intended for use in a conduit for supplying acetylene gas, I prefer a disk of aluminum, which has been found to be most 45 suitable for the purpose.

A convenient embodiment of my invention is illustrated in the accompanying drawings, but it is to be understood that changes in the details of construction may 50 be made within the scope of the specification and claims without departing from the principle of my invention.

In the drawings:—Figure 1 is a vertical longitudinal section of a valve construction

embodimenting my invention; Fig. 2 is a section 55 on the line 2—2 of Fig. 1; and Fig. 3 is a plan view of the relatively soft metal disk which is adapted to be placed above the seat of the valve.

Referring to the drawings:—1 designates 60 the valve body which is provided with the valve seat 2 and 3 designates the diaphragm which is fixed or secured in position above the valve seat by means of a screw plug 4. The diaphragm 3 is adapted to be depressed 65 against the seat 2 by means of a screw 5 for the purpose of closing the valve opening or channel.

Above the valve seat 2 and resting upon the same is a disk 6 of soft metal, as for 70 instance copper, aluminum or the like, the outer edge of which rests upon a shoulder 7 formed on the valve body. A ring 8 is placed between the disk 6 and the dia- 75 phragm 3. The said ring holds the dia- phragm a predetermined distance away from the disk 6 when the valve is open; that is, when the diaphragm is not depressed by the screw 5.

The disk 6 is provided with an opening 9 80 which registers with the inlet channel 10 of the valve; and it is also provided with a number of holes or openings 11 which are located over a circular groove or depression in the valve seat with which the outlet chan- 85 nel 12 communicates. It will be understood that in operation when the diaphragm 3 is out of contact with the disk 6 the gas passes from the inlet channel 10 under the dia- phragm 3 and out through the outlet chan- 90 nel 12.

By reason of the fact that the disk 6 consists of relatively soft metal while the dia- phragm consists of a relatively hard metal such as steel, the latter causes a complete 95 closure of the valve channel when it is de- pressed against the disk by the screw 5.

Should the disk 6 become so worn as to prevent the proper closure of the valve by the depression of the diaphragm 3, said disk 100 may be readily replaced by another one of similar construction merely by the removal of the screw plug 4.

While the disk 6 is shown as resting di- rectly upon the seat 2 of the valve, it will be 105 understood that it need not rest directly against the said seat but may be supported in proximity thereto, and it will be under-

stood also that the said disk may be secured in position by any other suitable and desirable means than that shown.

Having thus described my invention, I claim:—

1. In a diaphragm valve, the combination with the diaphragm and its seat of a disk of soft metal between the diaphragm and the seat and the said disk having a hole in registry with the inlet of the valve whereby communication may be established between the inlet and the outlet of the valve.

2. In a diaphragm valve the combination with the diaphragm and its seat of a disk of soft metal between the diaphragm and the seat, and the said disk having holes there-

through for establishing communication between the inlet and outlet of the valve.

3. In a diaphragm valve, the combination of a diaphragm member, a valve seat, a plate of relatively soft metal on the seat, and a ring interposed between the said diaphragm member and the said plate; on which ring the said diaphragm member is seated.

In testimony, that I claim the foregoing as my invention, I have signed my name in presence of two subscribing witnesses.

GUSTAF DALÉN.
